WELL COMPLETION

Bertie F. Birdwell, Austin, and Gerald G. Priest and Bryan E. Morgan, Houston, Tex., assignors, by mesne assignments, to Jersey Production Research Company, Tulsa, Okla., a corporation of Delaware

Application December 24, 1956, Serial No. 630,266

4 Claims. (Cl. 166—42)

The present invention is directed to a method for completing oil and gas wells. More particularly, the invention is directed to a method for completing oil and gas wells in which a drilling fluid or mud is used to control the well. In its more particular aspects, the invention is directed to a method for completing an oil or gas well in which a column of drilling fluid is maintained in a casing to control the well.

Current practice when completing wells, such as oil and gas wells, through perforated casings is to have drilling fluids, such as mud, salt water, water, or oil, in the well casing and to perforate the casing with bullet, shaped charge, chemical or punch-type perforators. When the pressure of a formation traversed by the well exceeds the hydrostatic pressure of a column of oil or water at the completion depth, it is customary to use weighted salt water or normal drilling mud having a density great enough to exceed formation pressure in order to control the well while perforating the casing and performing other routine completion operations. In the case of a well filled with drilling mud when the casing is perforated, the drilling mud flows into the perforations because of the pressure differential existing between the interior of the casing and the formation. The perforations are thereby partially or completely plugged with mud and this plugging is aggravated by the heat and instantaneous pressure evolved by the propellant powder in the case of bullet perforators and the high explosive in the case of the jet or shaped charge perforators. Where chemical or punch-type perforators are employed, it is not uncommon for the drilling mud to lose water rapidly to the formation resulting in the drilling mud becoming dehydrated and forming plugs. Data are available which indicate that such plugs whether formed by dehydration of the drilling mud by heat, and/or pressure or by loss of water to the formation are difficult to remove by subsequent flow from the formation into the well bore and that the productivity of a perforated interval in a producing formation is significantly reduced. Field completion attempts of wells indicate that such plugging of the perforations may cause formations to be tested as being non-productive and thereby condemned when actually the formation may contain economically producible oil or gas. Thus it is clear that the problem of plugging of perforations is serious and is a source of expense in well completions and of erroneous conclusions in exploratory work which may cause major hydrocarbon reserves to remain undiscovered.

Another problem which exists in perforating wells is that it is necessary to provide control of the well during perforations. This is accordingly accomplished by maintaining a hydrostatic column which exerts a pressure greater than the formation pressure exposed when the casing is perforated. However, to provide a column having a sufficient hydrostatic pressure, it is necessary to add

2

weighting agents such as barites, sand, and other solid heavy materials to the fluid column maintained in the well.

As it has become necessary to drill deeper and deeper wells in search for petroleum-producing formations, the temperatures encountered in these deeper wells have increased to an extent that difficulties have been encountered. For example, the fluids which heretofore have been used in wells become unstable and tend to lose their properties at the high temperatures of the order of 200° to 250° F., which may be encountered. For example, emulsions which may be used as completion fluids may become unstable and resolve into their component parts. It is, therefore, desirable to provide a heat-stable emulsion which will maintain and preserve its characteristics at high temperatures encountered in deep wells.

The high temperatures may be encountered in wells ranging from 10,000' to 25,000' in depth with a usual operation being performed at from about 14,000' to about 20,000'. High well temperatures may be encountered at lesser depths, for example, from 6,000' to about 14,000', depending on the area where the operations are being conducted.

In accordance with the present invention, the plugging 25 of perforations in well casing in which a column of drilling fluid or mud is maintained to control the well is eliminated by providing in the well casing adjacent the producing formation a body of a thermally stable emulsion, which effectively removes, displaces, or excludes the drilling fluid from that zone and allows perforations to be made in the casing without damaging the formation by contamination.

The present invention may, therefore, be briefly described as involving the placement of an emulsion of an 35 oily and aqueous medium containing a soluble weighting agent dissolved in one of the components of the emulsion, the emulsion being characterized by having a low fluid loss into the formation, having the property of displacing or excluding drilling fluid from the region of the casing 40 to be perforated or from the subsurface earth interval to be treated. The particular emulsion is a heat-stable emulsion in which an emulsifying agent selected from the alkali metal salts of purified lignin sulfonic acids containing from about 3% to about 33% by weight of sulfonate groups and from the ammonium and alkali metal salts of lignin sulfonic acids containing from about 38% to about 57% lignin sulfonic acid groups is employed.

Another problem exists in well recompletion and servicing operations in that, heretofore, existing perforations 50 in the wall of a well bore or a well casing penetrating into hydrocarbon-productive formations frequently were contaminated or damaged by conventional well fluids or well completion fluids while an operation such as treating, sealing or cementing, perforating, fracturing, and the like was carried on or performed elsewhere in the well such as in a vertically spaced part zone. Heretofore, there had been no satisfactory way of preventing damage to the existing perforated formation.

In accordance with the present invention, it has been found that such damage may be eliminated by placing 60 a body of an emulsion having a low fluid loss in contact with the perforations or perforated formation while conducting or performing operations elsewhere in the well. Hence, the present invention also contemplates the feature 65 of protecting or blanketing selected intervals or zones in the well while recompletion, servicing, sealing, or treating operations are conducted in the well either in

a zone or interval vertically removed from the emulsion-protected zone or in the emulsion-protected zone.

The emulsion employed in the practice of the present invention is used in the sense of the emulsions described in Sutheim's "Introduction to Emulsions," Chemical Publishing Company, Inc., Brooklyn, New York, 1947, page 1, where an emulsion is described as follows:

"Emulsions are intimate mixtures of two immiscible liquids, one of them being dispersed in the other in the form of fine droplets."

The emulsion of the present invention contains, dissolved in one of the components of the emulsion, a weighting agent which is soluble in one of the components. The weighting agent may be soluble either in the aqueous phase or the oily phase of the emulsion. For example, the water phase may contain a water-soluble, inorganic weighting agent.

The oily phase may suitably be a hydrocarbon, such as crude petroleum and fractions thereof, such as gasoline, kerosene, gas oil, diesel oil, and the like. Other hydrocarbonaceous materials or derivatives of hydrocarbons, such as carbon tetrachloride, and the like, may form all or part of the oily phase.

The emulsion may either be heavier or lighter than the drilling fluid and suitably may have a density in pounds per gallon in the range from about 7 to about 18 pounds per gallon. The emulsion where lighter than the drilling fluid may have a suitable viscosity sufficient to displace the drilling mud and to prevent displacement thereof by the drilling mud. For example, the viscosity of the emulsion replacing the drilling mud may range from about 10 to about 4000 centipoises at 60° F.

The emulsion of the present invention is suitably formed by employing an emulsifying agent of the type known as the Polyfons and the Orzans. The Polyfons are a series of surface-active chemicals formed from purified lignin. These surface-active agents may be the alkali metal salts such as sodium, potassium, and lithium of lignin sulfonic acid. The commercially available Polyfons are sodium lignosulfonates and may be identified as follows:

Grades	Percent Sodium Sulfonate Groups
Polyfon XQ	2.9
H	5.8
O	10.9
T	19.7
R	26.9
F	32.8

purified uniform pine wood lignin is obtained as a by-product of pulping wood chips with a caustic solution to separate and recover the pure lignin, which is then sulfonated with a sulfonating agent such as fuming sulfuric acid. In the manufacture of Polyfons, sugars, hemi-celluloses, and other degradation products are removed in the lignin-isolating operation and thus are not found in the Polyfons. In a word, the Polyfons are the alkali metal salts of lignin sulfonic acids having from about 3% to about 33% by weight of sulfonate groups.

The Orzans are surface active chemicals derived from the by-products of wood pulping by the sulfite process using an ammonia base. The Orzans contain from about 20% to about 40% by weight of ash and contain varying amounts of sugars. In this process wood chips consisting of about 90% western hemlock and 10% white fir are placed into a digester containing ammonium bisulfite and excess sulfur dioxide. The mixture is cooked for about 8 hours at a temperature of about 290°-300° F., while a pressure of about 70 to 80 pounds per square inch is maintained within the digester. After the cooking period, the mixture is filtered to separate the wood pulp from the bisulfite liquor.

Orzan A is obtained by concentrating the liquor by evaporation to about 50% solids, and then spray-drying the concentrated liquor. Orzan A, therefore, is an unaltered by-product of the pulping process containing ammonium lignin sulfonate and wood sugars.

Orzan S is a sodium salt of lignin sulfonic acid and is obtained by adjusting the concentrated ammonium bisulfite liquor to pH 7.0-7.5 with sodium hydroxide. At a pH of 7.0-7.5 the excess ammonia is driven off and the concentrated liquor is spray-dried to obtain a free flowing powder.

The Orzans AH0, AH1, AH2, and AH3 are made by partially polymerizing the lignin sulfonate units present in Orzan A, increasing the average molecular weight from about 10,000 to about 40,000. The member having the highest molecular weight is Orzan AH3.

A complete description of methods used in the isolation of lignins and the various lignin sulfonates by the kraft, soda and sulfite processes will be found in the work by Ott, Spurlin, and Graffin, entitled "Cellulose and Cellulose Derivatives," Interscience Publishers, Inc., New York, second edition, part 2, pages 524 to 545.

The by-products from this process are ammonium lignin sulfonates and sugars, occurring in a fixed proportion. The Orzans available in the industry and employed in the present invention have a composition as shown in the following table:

TABLE I

A comparison of the chemical composition of the various Orzans

Trade Designation	Type of Compound	Constituent Analysis—Percent Total Solids					
		Lignin Sulfonic Acids	Reducing Sugar	Available Ammonia	Sulfate	Sulfated Ash	Ash
Orzan-A	Ammonium Lignin Sulfonate	55	16.7	2.8	1.6	2.0	21.9
Orzan-S	Sodium Lignin Sulfonate	49	10.6	0.2	1.69	23.0	18.5
Orzan-AH0	Polymerized Ammonium Lignin Sulfonate (Orzan A).	55.2	12.9	2.58	1.52	0.5	21.3
Orzan-AH1	do	55.5	10.7	2.58	1.55	8.3	21.4
Orzan-AH2	do	55.8	9.5	2.65	1.57	8.3	22.2
Orzan-AH3	do	56.7	9.0	2.65	1.60	7.7	22.4
Orzan-SS	Sodium Lignin Sulfonate	38.4	0.0	0.004			41.3

The extent of sulfonation of the Polyfons is controlled to form the intermediate components having the degree of sulfonation indicated before. To form the Polyfons, 75

Thus, it can be seen that the Orzans vary in their degree of sulfonation and the amount of sugars associated with them. By processing the ammonium lignin

sulfonates with sodium hydroxide, it is possible to form the alkali metal salt which is substantially free of sugar.

There are many water-soluble, inorganic weighting agents which find use in the practice of the present invention, among which may be mentioned, by way of illustration and not by way of limitation, alkali metal carbonates, alkali metal chlorides, zinc chloride, calcium chloride, and sodium chloride which are particularly useful. Examples of the water-soluble inorganic weighting agents are presented in the following table:

soluble organic weighting agents suitably have a specific gravity in the range from about 1.2 to about 4. These organic weighting agents are illustrated in the following table:

The emulsion employed in the present invention will suitably consist essentially of from about 5% to about 95% by volume of water with a preferred range from about 20% to about 80% by volume of water, from about 5% to about 95% of oil with a preferred range from about 20% to 80% volume percent of oil, and an emulsifying agent of the type illustrated in an amount

There are many oil-soluble organic weighting agents which are soluble in the oily phase of the emulsion employed in the practice of the present invention. The oil-

in the range from about 0.5 to about 20 grams per 100 ml. of the external phase of the emulsion.

The weight percent of the inorganic weighting agent or salt dissolved in the aqueous or water phase will range from 1% up to about saturation, while the weight percent of organic compound or weighting agent dissolved in the oil phase will range from 1% up to about saturation.

It is contemplated that weighting agents may be present in both the oily and aqueous phases of the emulsions. However, conditions may exist where the weighting agent is present in only one phase of the emulsion.

The present invention will be further illustrated by reference to the drawing, in which:

Figs. 1 to 6, inclusive, represent a stepwise operation in accordance with the invention; and

Figs. 7 to 11, inclusive, represent another mode of practicing the invention.

Referring to the drawing in which identical numerals will be employed to designate identical parts, and particularly to Figs. 1 to 6, numeral 11 designates a well drilled from the earth's surface, not shown, to penetrate a plurality of subsurface earth intervals 12, 13 and 14. The well is lined with a well casing 15, which may be cemented in place with cement 16. The well casing 15 and the cement 16 may be perforated in the earth interval 14 to form perforations 17 to allow communication between the formation or zone 14 and the interior of the casing 15 to produce, for example, oil, gas and other desirable earth minerals. A tubing 18 may be placed in the casing 15 with its lower end 19 immediately above the plurality of subsurface earth intervals, sands, zones, strata, horizons, or formations 12, 13 and 14. It may be assumed for purposes of this description that the intervals 12 and 14 may be productive of hydrocarbons, while the interval 13 may be non-productive. In the showing of Fig. 1 the well has been drilled and contains drilling fluid or other fluid which may be used for control, such as salt water indicated by the numeral 20.

In Fig. 2, it is desirable to perform an operation in the well, but yet it is also desirable to protect the perforations 17 against damage. For example, if mud were allowed to come into contact with the perforations 17, damage to the formation or interval 14 might occur which could effectively prevent production of hydrocarbons from the zone 14. It may be assumed for purposes of this description that it is desirable to perform a cementing operation to prevent communication from back of the casing with the perforations 17 from the interval either 12 or 13. To this end a tubing extension member, such as 21, may be lowered on a suitable wire line, not shown, and located adjacent the lower end 19 of the tubing 18. The tubing extension 21 may suitably be landed, anchored, or supported in the lower end 19 in a suitable landing nipple or other supporting means, such as 22. By anchoring and sealing the extension member 21 in the lower end 19 of the tubing 18, the effective length of the tubing 18 is increased. A body of emulsion, such as 23, then may be placed adjacent the perforations 17 displacing the fluid 20 up the annulus A between the tubing 18 and the casing 15. It will be seen by placing an emulsion of the type indicated before adjacent the perforations 17, the perforations 17 are effectively blanketed and protected. Thereafter, the tubing extension 21 is removed from the tubing 18 by attaching a wire line, not shown, to the fishing head 24 and retrieving same from the tubing. As shown in Fig. 3, a gun perforator 25, which may be of the shaped charge or bullet type, is lowered on the wire line 26 to perforate the interval 12. The perforator 25 may be one of the chemical or mechanical types, but preferably is a bullet gun or a shape charge gun. The perforator 25 is then operated or fired to form perforations 27 in the casing 15, cement 16, and to penetrate the interval 12. Thereafter, the perforator 25 is re-

trieved from the tubing 18 by wire line 26 and a body of cement 28 is then placed adjacent the perforations 27 and squeezed outwardly to fill the perforations 27 and any channels between the wall of the wellbore 11 and the casing 15 to prevent communication with the perforations 17. After the cement has been squeezed by imposing pressure on the body 28, the excess cement may be removed by employing a tubing extension member, such as 21, and to remove the excess cement which may be of a modified type having a low fluid loss and which remains fluid for a sufficient length of time to allow circulation of the cement out. A suitable modified cement is described in the patent to Salathiel, U.S. Patent No. 2,582,459. After the fluid cement has been removed, the perforations 27 are effectively sealed, as indicated, and it becomes desirable to remove the body of emulsion 23. This is also accomplished by placing a tubular extension member, such as 21a, in the landing nipple 22 and circulating the emulsion out as indicated by the arrows shown in Fig. 5 using a suitable circulating fluid. Thereafter on removal of the emulsion, production may again be had from the interval 14, which has been protected during the operations from damage by contact with fluids in the well. This flow is shown as indicated by the arrows. The emulsion may be flowed outwardly without the use of a tubing extension by suitably swabbing the well.

Referring now to Figs. 7 to 11, 11 designates a well drilled from the earth's surface, not shown, to penetrate a plurality of subsurface earth intervals 12, 13 and 14. The well is lined with a well casing 15, which is cemented in place with cement 16. The well casing 15 and the cement 16 has been perforated previously in the earth interval 14 to form perforations 17 to allow communication between the formation or zone 14 and the interior of the casing 15 to produce, for example, oil, gas and other desirable earth minerals. A tubing 18 is in the casing 15 with its lower end 19 immediately above the perforations 17. This condition is illustrated in Fig. 7.

For purposes of explanation, it is desirable to protect these perforations 17 opposite the formation 14 while new perforations are to be made in formation 12. Salt water 20 is pumped into tubing 18 until the annulus 30 is either filled with salt water or the hydrostatic column becomes balanced with the formation pressure in the formation 14. This step of the operation is illustrated in Fig. 8.

A predetermined quantity of emulsion, according to this invention, is pumped through tubing 18 until the emulsion reaches the lower end of the tubing 19. At this point, the casing side is closed at the surface and the emulsion in tubing 18 is displaced by pumping salt water into tubing 18 until the emulsion 23 contacts the face of formation 14 through perforations 17. Further displacement of the emulsion is made to cover formations 12, 13 and 14, as illustrated in Fig. 9.

Tubing 18 is withdrawn from the well and perforator 25 is lowered into the well opposite formation 12 and fired to make perforations 31, as illustrated in Fig. 10.

The perforator is removed from the well and tubing 18 with packer 32 is lowered into the well. The packer 32 is set as shown in Fig. 11 to accomplish dual completion of the well. Hydrocarbon production from formation 12 through perforations 31 is directed into the annulus between the tubing 18 and the casing 15 while production of hydrocarbons from formation 14 through perforations 17 occurs through the inside of tubing 18.

In order to illustrate the invention further, a number of compositions were prepared in accordance with the present invention. These compositions are set out in the following table:

TABLE IV—Continued on following page.

It may be seen from an examination of the data in the immediately preceding table that these emulsions have very low fluid losses at room temperatures and after aging at 250° F. By way of explanation, emulsions having a fluid loss above 40 ml. in 30 minutes at room temperature after the sample has been aged for 24 hours at 250° F., or those having a fluid loss above 80 ml. in 30 minutes at a test temperature of 250° F., may be considered unsatisfactory as well completion fluids under some conditions, since they may not remain in place to protect the exposed face of a subsurface interval.

It is to be particularly noted that the Polyfon- and Orzan-containing emulsions are particularly suitable after both atmospheric and elevated temperature aging and, therefore, are useful as completion and servicing fluids in wells of normal and elevated temperatures.

In the composition of the present invention, it is desirable to stabilize the emulsion, and this may suitably be done by employing suitable stabilizing agents which may be of dispersible solid material and which may be identified as Pozmix, Pozmix 140, line, Xact clay. Other stabilizing agents such as polyvinyl alcohol in admixture

with the Pozmix and the lime, Zeogel clay and calcium hydroxide may also be used. These several dispersible solids are particularly desirable at the elevated temperatures encountered in deep wells and may be used in amounts from about 0.5 gram to about 3.0 grams per 100 ml. of the aqueous phase.

The compositions of the present invention are quite useful as perforating fluids and well completion fluids and have the property of protecting the formation and preventing damage of the formation by eliminating contact with contaminating bodies. For example, when the composition of the present invention is used as a perforation fluid, the permeability of the formation is not damaged and flow is readily obtained therefrom. Furthermore, the composition of the present invention allows formations to be protected while conducting operations in the well displaced from the protected formation.

While the invention specifically contemplates its use and application to perforating, servicing, and completion operations in cased wells, it is understood that these applications and uses are given by way of illustration and not by way of limitation. Thus, the present invention

^a Sample aged in a closed cylinder at 250° F. for 24 hours or longer, then cooled to room temperature and tested.^b Tested in a Baroid high-temperature filter press; result doubled to convert it to regular API basis.

is applicable to fracturing of subsurface earth intervals; the invention may also be used in treatment of a selected zone pierced by a well with a chemical to improve the characteristics of a selected zone, with the emulsion being used to protect or blanket another selected zone to prevent damage thereto or to prevent change of character of the protected zone.

The present invention may suitably be used in dual or multiple completions where there may be fluid communication between vertically spaced apart zones, the improved emulsion being used to protect one zone while a remedial or sealing operation is conducted in the other zone.

It is also important in the present invention that, whenever operations are conducted in a well, the emulsion is the first fluid, other than the desired mineral, such as oil and/or gas, which contacts the exposed perforations. Thus, it is specifically contemplated that the emulsion may be used to contact the perforations and protect same following which drilling fluid, mud, salt water, and the like may then be flowed past the protected perforations which may contain the emulsion. The emulsion thus protects the clean perforation, without damaging the earth interval and without losing fluid thereto.

It is also within the purview of the invention to conduct all workover operations using the present invention

50 with the improved emulsion protecting exposed faces of earth intervals undergoing servicing or reworking. However, the emulsions of the present invention may be used with other well fluids so long as the exposed interval is protected against damage by contact with the detrimental fluid.

55 The nature and objects of the present invention having been completely described and illustrated, what we wish to claim as new and useful and to secure by Letters Patent is:

60 1. A method for completing and servicing a well containing drilling fluid in which high temperatures of the order of 200° to 250° F. are encountered which comprises placing in said well an emulsion, containing from about 5% to about 95% by volume of an aqueous medium, from about 5% to about 95% by volume of an oily medium, a weighting agent in an amount within the range between about 1% by weight to about saturation dissolved in at least one of said media, and an emulsifying agent selected from the alkali metal salts of purified lignin sulfonic acids, in which sugars, hemicelluloses, and other degradation products have been removed, containing from about 3% to about 33% by weight sulfonate groups and ammonium and alkali metal salts of lignin sulfonic acids containing from about 38% to about 57% lignin sulfonic acid groups in an amount in the range between 0.2 and

about 20 grams per 100 ml. of the external phase of the emulsion, said emulsion having a density in the range from about 7 to about 18 pounds per gallon and different from that of the drilling fluid and a viscosity at 60° F. in the range from about 10 to about 4,000 centipoises, displacing a portion of said drilling fluid in said well from a point adjacent a selected subsurface interval penetrated by said well, contacting an exposed face of said selected subsurface earth interval at said point with said emulsion to protect said exposed face against contamination with said drilling fluid such that the emulsion is the first fluid other than hydrocarbons which contacts said exposed face, performing an operation in said well, said emulsion being subjected to said temperatures of the order of 200° to 250° F. in said well and being maintained in contact with said exposed face while said operation is being performed, said emulsion being characterized by having a low filtration rate and by not damaging said earth interval, said emulsion being stable at said temperature, removing said emulsion from said exposed face after completion of said operation, and then producing hydrocarbons from said exposed face.

2. A method in accordance with claim 1 in which the operation in said well comprises the placing and operation of a perforator in said emulsion to penetrate the selected earth interval.

3. A well completion composition which comprises an emulsion containing from about 5% to about 95% by volume of an aqueous medium, from about 5% to

about 95% by volume of an oily medium, a weighting agent in amount within the range from about 1% by weight to about saturation dissolved in at least one of said media, and an emulsifying agent in an amount in a range between about 0.2 and about 20 grams per 100 ml. of the external phase of the emulsion selected from the group consisting of alkali metal salts of purified lignin sulfonic acids, in which sugars, hemicelluloses, and other degradation products have been removed, containing from about 3% to about 33% by weight sulfonate groups and ammonium and alkali metal salts of lignin sulfonic acids containing from about 38% to about 57% by weight lignin sulfonic acid groups, said emulsion being heat stable at well temperatures of the order of 200° to 250° F.

4. A composition in accordance with claim 3 in which the agent is a high specific gravity halogenated hydrocarbon dissolved in the oily phase of the emulsion.
